UNITED STATES PATENT OFFICE

VALENTINE H. SMITH, OF PHILADELPHIA, PENNSYLVANIA.

DESIGN FOR NURSING-BOTTLE.

Specification forming part of Design No. **7,992**, dated January 5, 1875; application filed December 24, 1874.
[Term of Patent 7 years.]

To all whom it may concern:

Be it known that I, VALENTINE H. SMITH, of the city and county of Philadelphia and State of Pennsylvania, have invented a Design for Nursing-Bottles, of which the following is a specification:

The nature of my design is fully represented in the accompanying photographic illustration, to which reference is made.

The bottle is of glass, and its body *a* is in the form of a doll or child. The mouth or

neck *b* of the bottle is a tubular projection at the head of the body *a*.

What I claim as my invention is—

The design for a glass nursing-bottle of the form of a doll or child, as shown and described.
